UNITED STATES PATENT OFFICE.

GUSTAV A. J. MEYER, OF CHICAGO, ILLINOIS, ASSIGNOR TO MEYER & WENTHE, A CO-PARTNERSHIP CONSISTING OF GUSTAV A. J. MEYER AND HERMAN H. WENTHE, OF CHICAGO, ILLINOIS.

LABEL HOLDER FOR SELF-INKING STAMPS.

Application filed July 31, 1925. Serial No. 47,300.

To all whom it may concern:

Be it known that I, GUSTAV A. J. MEYER, a citizen of the United States, and residing at Chicago, in the county of Cook and State 5 of Illinois, have invented a new and Improved Label Holder for Self-Inking Stamps, of which the following is a specification.

My invention relates to self-inking stamps 10 and more particularly to means for labeling such stamps to indicate the wording of the imprinting plate, the color of ink on the inking cushion, and the direction in which the imprinting plate faces.

Where a number of self-inking stamps are used by one party, they are apt to be confused with one another, so that considerable time is often wasted in making an initial impression of one or more of the stamps in order to select the desired one. Owing to the 20 general construction of the frame work of such stamps, it usually is not feasible to affix an imprint of the die to this frame work as a suitable indication, and in many cases 25 the affixing of merely a portion of the imprint would not clearly distinguish the stamp from others of the same general kind.

Moreover, while a portion of the imprint of the die might be pasted or cemented to 30 a part of the frame work of an ordinary self-inking stamp, this would soon become so smeared and soiled as not to be clearly legible and also would be easily damaged during the quick handling of the stamp as 35 a whole. For these reasons, self-inking stamps have generally been left unlabeled, thereby leading to frequent confusion, to a waste of time on the part of users in checking the imprints of different stamps while 40 selecting a desired one, and to a spoiling of documents by inadvertently using wrong stamps.

My present invention aims to overcome all 45 of these difficulties by means of a simple and easily employed construction which will not add materially to the cost of the complete self-inking stamp and which will permit the continuous displaying of the entire imprint of the stamp.

More particularly, my invention provides

a self-inking stamp having its handle constructed for displaying the entire imprint of the die of the stamp; provides easily attached means for simultaneously securing an imprint of the stamp to handle and for 55 protecting this imprint both against soiling and against damage by handling; and provides simple means for insuring a proper attaching of the imprint and its protecting cover. Still further and also more detailed 60 objects will appear from the following specification and from the accompanying drawings, in which—

Fig. 1 is a perspective view of a self-inking stamp provided with the imprint- 65 holding and imprint-shielding means of my invention and having its handle specially constructed for this purpose.

Fig. 2 is an enlarged central and longitudinal section taken through the handle 70 member of the stamp of Fig. 1.

Fig. 3 is a transverse section through the handle member, taken along the line 3—3 of Fig. 2.

Fig. 4 is an enlarged perspective view of 75 the attaching member used for fastening the imprint and its protecting shield to the handle.

Fig. 5 is an enlarged transverse section through this attaching member, taken along 80 the correspondingly numbered line in Fig. 4.

In accomplishing the purposes of my invention according to the accompanying drawings, I provide the handle of the self-inking stamp with a cylindrical portion 1 85 having a height and circumference at least as large as the width and length respectively of the most distinctive portion of the lettering die of the stamp. Then I provide a transparent cover or shield 2, desirably made 90 of celluloid or the like, and also of a size corresponding to the height and circumference of the cylindrical handle portion.

To label the stamp, I first make an imprint of the die on a slip of paper 3 corresponding in size to the celluloid shield, superpose the shield on this imprinted slip, and wrap the two jointly around the cylindrical stem 1 of the handle. Then I affix 95 the imprinted slip and the protecting shield 100

- simultaneously to the handle by an attaching member, which member preferably also covers the juncture of the free ends of the superposed imprint strip and shield. This 5 attaching member desirably is formed of a plurality of staples having their backs connected by a metal strip which is integral with the staples, thereby constituting the series of staples 4 connected by a back strip 10. 5. To increase the effectiveness of this securing device, I also desirably arch the connecting or back portion 5 slightly in the same direction as the prongs of the staples, as shown in Fig. 5, thereby causing the 15 edges of the back portion 5 to be pressed firmly against portions of the transparent shield 2 when the fastening member is applied by driving it radially inward of the handle stem 1 so as to anchor the prongs 20 of the staples in the wood. In practice, the superposed imprint strip and shield are desirably wrapped around the stem of the handle so that their adjacent free ends will be disposed at the back of the stamp, thereby 25 locating the attaching member also at the back of the stamp where it furnishes a ready indication of the direction in which the stamp faces.
- To facilitate a proper attaching of the imprint strip and the shield, and to prevent both from shifting on the handle, I preferably provide the handle with a pair of circumferential beads 7 and 8 spaced by a 30 distance corresponding to the common width 35 of the imprint and the shield, thereby securing a rigid and non-shifting fastening of these attached portions by the application of the single attaching member.
- With the arrangement thus described, it 40 will be obvious that the distinctive imprint of the stamp can readily be displayed on the handle, thereby avoiding all chances for confusion between stamps having different legends. Moreover, the same size of handle 45 can be used on a group of several different sizes of stamps when the handle is proportioned in size to the distinctive imprint of the largest stamp of that group. So also, the resulting labeling will indicate the color 50 of the inking pad on that stamp, thereby making it easier to distinguish between stamps which are somewhat similar as to their wording but which are used in connection with different colors of inks.
55. In practice, the entire cost of affixing such an indicating label to each self-inking stamp is a quite small item in comparison with the total cost of the stamp, so that it need not increase the retail cost at all, although affording decided advantages for the users.
- Moreover, since quite a variety of die plates 60 are commonly used with self-inking stamps of a given type of frame, the same distinctively proportioned handles as well as the 65 same sizes of imprint slips, transparent

shields and metal attaching members can readily be employed with all stamps having a given size of frame. So also, the handle construction, although differing from the conventional ones in shape, can readily be 70 made ornamental, so that the employment of my invention need not detract from the general appearance of the complete self inking stamp.

However, I do not wish to be limited to 75 the particular shape of parts herewith illustrated, or to the above described details of construction and arrangement, as changes might obviously be made without departing either from the spirit of my invention or 80 from the appended claims.

I claim as my invention:—

1. A self-inking stamp embodying a handle having a cylindrical portion; a strip imprinted with at least a portion of the 85 die plate and wrapped around the said handle portion, a transparent shield overlapping the said strip and having its ends adjacent to each other, and means simultaneously securing the said strip and shield to 90 the handle and overlapping the junctures of the ends of the shield.

2. A self-inking stamp embodying a handle having a cylindrical portion; a strip imprinted with at least a portion of the die- 95 plate and wrapped around the said handle portion, a transparent shield overlapping the said strip, and fastening means for simultaneously securing the said strip and shield to the handle, the fastening means comprising a single-piece member having a portion straddling the juncture of the ends of the shield and having prongs extending through both the shield and the strip into the handle.

3. A self-inking stamp embodying a vertical handle having a cylindrical portion, a strip imprinted with at least a portion of the die-plate and wrapped around the said handle portion, a transparent shield overlapping the said strip, and fastening means for simultaneously securing the said strip and shield to the handle, the fastening means comprising in integral formation a plurality 110 of staples spaced vertically of the handle and each spanning the adjacent ends of the shield, and strip portions extending between the successive staples vertically of the handle and likewise spanning the said adjacent ends, the said strip portions being 115 concave in horizontal section towards the handle.

4. A self-inking stamp embodying a handle having a cylindrical portion, a strip imprinted with at least a portion of the 125 die-plate and wrapped around the said handle portion, a transparent shield overlapping the said strip, the handle having shoulder formations disposed at opposite ends of the said cylindrical portion and 130

spaced by a distance corresponding to the width of the transparent shield; and fastening means for simultaneously securing the said strip and shield to the said handle portion, the fastening means comprising a metal strip abutting at its ends against the said shoulders and provided with prongs ex-

tending through both the shield and the imprinted strip at opposite sides of the junction of the ends of the shield.

10

Signed at Chicago, Illinois, July 25th, 1925.

GUSTAV A. J. MEYER.
